(57) **CLAIM**

The ornamental design for an illuminated ornament with an interchangeable star faceplate, as shown and described.

DESCRIPTION

FIG. 1 is a front perspective view of an illuminated ornament with an interchangeable star faceplate showing my new design;

FIG. 2 is a right side elevation view thereof;

FIG. 3 is a left side elevation view thereof;

FIG. 4 is a bottom plan view thereof;

FIG. 5 is a top plan view thereof;

FIG. 6 is a front elevation view thereof; and,

FIG. 7 is a rear elevation view thereof.

The dash-dash broken lines shown in the drawings depict portions of the illuminated ornament with an interchangeable star faceplate that form no part of the claimed invention. The dash-dot-dash broken line represents a boundary around a portion of the illuminated ornament with an interchangeable star faceplate that forms no part of the claimed design.
